APPARATUS FOR INJECTING GRAPHITE
INTO ENGINES

Carl R. Rolen, Waukesha, Wis.

Application November 23, 1933, Serial No. 699,309

19 Claims. (Cl. 123—196)

This invention relates to apparatus for injecting graphite into the combustion chamber of an internal combustion engine.

It is well known that a thin coating of graphite over the inner walls of the cylinders, the valves, and other internal mechanism of internal combustion engines, effects a very material improvement in the operation of the engine. Such a coating of graphite retards carbon formation as carbon will not readily adhere to a graphite surface. It affords added lubrication and also improves the compression of the engine by forming a more effective seal at the piston rings and the valves.

Heretofore, it has been the custom to add a solution of colloidal graphite in oil directly to the crank case lubricant, relying upon the oil circulating through the engine to convey the graphite to the desired locations. While this method of applying graphite to an internal combustion engine resulted in some of the graphite reaching the desired destination, much of its beneficial effect was lost by carrying it in an oil suspension.

It is, therefore, an object of this invention to provide an apparatus whereby dry powdered graphite may be effectively injected into an internal combustion engine and particularly into the combustion chamber thereof.

A further object of this invention is to provide an apparatus for the purpose described which affords a container or reservoir for a supply of dry finely powdered graphite, and which is so constructed and associated with the engine that the engine suction draws the powdered graphite into its combustion chamber.

Another object of this invention is to provide novel means for governing the flow of graphite into the engine.

In this respect, it is a further object of the invention to utilize a barrier of felt or similar material to control the flow of powdered graphite into the engine.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated two complete examples of the physical embodiment of my invention constructed accord-

ing to the best modes I have so far devised for the practical application of the principles thereof, and in which:

Figure 1 is a side elevation illustrating diagrammatically the intake manifold of a carburetor of an internal combustion engine, showing the application of this invention thereto;

Figure 2 is an enlarged side view of the apparatus with parts broken away and in section; and

Figure 3 is a fragmentary section view illustrating a slightly modified embodiment of the invention.

Referring now more particularly to the accompanying drawing in which like numerals indicate like parts throughout the several views, the 15 numeral 5 designates the intake manifold of a conventional internal combustion engine (not shown). Connected to the manifold is a carburetor 6, and communicated with the manifold and supported thereby is the device of this invention indicated generally by the numeral 7.

In the present instance, the device 7 is connected to the manifold above the throttle valve, that is, between the throttle valve and the engine. It may, however, be attached directly to 25 the carburetor outwardly of the throttle valve if found desirable and convenient, the major requirement being that sufficient vacuum is created within the interior of the device 7 by the engine suction.

The device 7 comprises a head 8 of inverted cup shape having an outlet duct 9 secured therein, which also attaches to the manifold or carburetor, as shown, and if desirable, may be utilized to support the entire device. The mouth 35 of the bore 10 in the head 8 is counterbored to define a shoulder 11 and the counterbore is internally threaded as at 12 for attachment to the open top of a container 13. The container 13, which may be in any desired form, holds a quantity of finely powdered dry graphite 14.

Confined between the shoulder 11 and the open end 15 of the container, is the flange 16 of an internal hood 17. Gaskets 18 of cork or other suitable material are disposed on opposite sides 45 of the flange 16 to afford a tight seal upon tightening of the container to the head 8.

The internal hood 17 is open at its bottom and communicates with the interior of a felt sleeve 19 which is clamped against the bottom of the 50 hood by a washer 20 supported on the lower end of a central stud 21. The stud 21 is carried by the head 8 and extends axially down through the hollow hood 17 and the felt sleeve 19, and has a clamping nut 22 on its lower threaded end by 55

which the washer 20 may be drawn upwardly toward the hood to compress the felt sleeve to any desired state of compression. Confined between the washer 20 and the hood 17 is an expansive spring 23, which acts in opposition to the adjusting nut 22 to afford a finer adjustment.

The hood 17 has an opening 24 communicating with the bore 10 of the head which being communicated with the intake manifold, is subjected to the influence of engine suction. The interior of the hood 17 by virtue of its communication through the opening 24 with the bore 10, is also subjected to the influence of engine suction so that a partial vacuum is established therein to draw the finely powdered graphite through the felt sleeve for conveyance into the combustion chamber.

In view of the finely powdered state of the graphite, it is evident that as long as some graphite remains in the container, the normal jarring of the automobile will cause it to be thrown upwardly onto the outer wall of the felt sleeve from which it is drawn through the interstices of the felt by engine suction. If desired, 25 the device may be mounted in an inverted position or at any convenient angle, without affecting its operation.

Inasmuch as the only communication between the interior of the hood 17 and the container 13 is through the interstices or pores of the felt sleeve and as the state of compression of the felt sleeve is readily adjustable, it is possible to control the rate of flow of the powdered graphite into the hood to a very fine degree, thus insuring that only the desired small quantity of graphite is taken into the combustion chamber.

Obviously, the effect of suction upon the device varies with the size and type of engine with which it is used, and to make the device more universal in its application, it may be equipped with valved air bleeds leading into the interior of the head and also into the interior of the container 13.

The provision of such air bleeds is illustrated in the modified embodiment shown in Figure 3. 45 As here shown, the head has an air inlet passage 25, in which a bushing 26 is secured. Threaded in the outer end of the bushing is an adjusting screw 27 having a pointed end to determine the degree of communication between the bushing bore and a transverse bore 28 leading to the atmosphere. The container 13 has a similar bushing 26 secured thereto and also equipped with a screw 27 to adjust the extent of the air bleed into the container interior.

55 By providing these air bleeds into the interior of the container and into the interior of the head 8, it is possible to adjust the effect of the suction on the device and thereby better regulate the flow of graphite into the engine.

60 As will be readily apparent, the container 13 may be quickly detached from the head to permit the same to be refilled with powdered graphite, and as the internal hood 17, together with the felt sleeve and its associated structure, are 65 supported from the head 8, by the stem 21, the removal of the container does not disturb the same.

70 It is noted that the opening 24, which communicates the interior of the hood 17 with the hollow cap or head is disposed diametrically opposite the outlet duct 9. This location of the opening 24 precludes the possibility of contact of liquid fuel which might enter the interior of the head through the duct 9, with the felt sleeve 75 19.

From the foregoing description taken in connection with the accompanying drawing it will be readily apparent to those skilled in the art, that this invention affords a novel device for injecting dry graphite into the combustion chamber of an internal combustion engine, and that by reason of the novel means employed to control the flow of the powdered graphite, its passage into the combustion chamber may be finely regulated.

What I claim as my invention is:

1. In combination with an internal combustion engine part subjected to engine suction, a container for dry powdered material which it is desired to inject into the internal combustion engine, means to communicate said container with said engine part, and a fibrous barrier through the interstices of which the powdered material must pass in its passage to the engine part.

2. In combination with an internal combustion engine part subjected to engine suction, a container for dry powdered material which it is desired to inject into the internal combustion engine, means to communicate said container with said engine part, and a felt barrier through which the powdered material must pass in its passage to the engine part.

3. In combination with an internal combustion engine part subjected to engine suction, a container for dry powdered material which it is desired to inject into the internal combustion engine, means to communicate said container with said engine part, and a felt barrier through which the powdered material must pass in its passage to the engine part, and adjustable means to compress said felt barrier and thereby determine the rate of flow of the powdered material therethrough.

4. A device for supplying finely powdered material in small quantities comprising, a container to hold a supply of the powdered material, an outlet through which the material may be drawn from the container by suction, and a fibrous barrier through which the material must pass before leaving the outlet, said barrier being of substantial density to restrict the flow of the material through its interstices to a fine seepage.

5. A device for supplying finely powdered material in small quantities comprising, a container to hold a supply of the powdered material, an outlet through which the material may be drawn from the container by suction, a fibrous barrier through which the material must pass before leaving the outlet, said barrier being of substantial density to restrict the flow of the material through its interstices to a fine seepage, and adjustable means to compress said barrier to determine its density and consequent rate of seepage of the material therethrough.

6. In combination with a passage through which finely powdered dry material is conveyed pneumatically, a felt barrier to control the rate of flow of the material through said passage.

7. In combination with a passage through which dry finely powdered material is conveyed pneumatically, a felt barrier to control the rate of flow of the material through said passage, the density of the barrier determining the rate of flow of the material therethrough, and adjustable means to compress said felt barrier to adjust its density.

8. A device for providing controlled injection of dry powdered material into a chamber subjected to suction comprising, a receptacle to hold a supply of said powdered material, means to

communicate the receptacle with said chamber, and a felt barrier closing the communication between the said communicating means and the receptacle, except for the fine passages afforded by the interstices in said felt barrier, whereby the powdered material must pass through said felt barrier to reach the communicating means.

9. A device of the character described comprising, a receptacle, a hollow head closing the receptacle, and a felt barrier between the receptacle and the interior of the hollow head, whereby the passage of dry powdered material from the receptacle into the hollow head is restricted and controlled.

10 15. 10. A device for providing controlled injection of dry powdered material into a chamber subjected to suction, comprising, a receptacle to hold a supply of the dry powdered material, a hollow head closing the receptacle, means to communicate the interior of the hollow head with the chamber, whereby the effect of suction in the chamber is also present within the hollow head, and means to separate the interior of the hollow head from the receptacle including a felt barrier, whereby the flow of material from the receptacle into the hollow head in response to the effect of suction therein is limited to the amount which will pass through the interstices of the felt barrier.

30 35. 11. A device for providing controlled injection of dry powdered material into a chamber subjected to suction, comprising a receptacle to hold a supply of the dry powdered material, a hollow head closing the receptacle, means to communicate the interior of the hollow head with the chamber, whereby the effect of suction in the chamber is also present within the hollow head, and means to separate the interior of the hollow head from the receptacle including a fibrous barrier extending down into the receptacle to be at all times covered with the powdered material enabling the suction within the hollow head to draw the powdered material through the fibrous barrier and into the hollow head.

40 45. 12. A device for providing controlled injection of dry powdered material into a chamber subjected to suction, comprising a receptacle to hold a supply of the dry powdered material, a hollow head closing the receptacle, means to communicate the interior of the hollow head with the chamber, whereby the effect of suction in the chamber is also present within the hollow head, a metal wall separating the receptacle interior from the hollow head except for a restricted passage, and a chamber formed partially by a felt wall with which the hollow head communicates through said restricted passage, the interstices in the felt wall forming the sole communication between the chamber and the receptacle interior so that the flow of powdered material into the hollow head is controlled by the density of said felt wall.

50 55. 13. A device for providing controlled injection of dry powdered material into a chamber subjected to suction, comprising a receptacle to hold a supply of the dry powdered material, a hollow head closing the receptacle, means to communicate the interior of the hollow head with the chamber, whereby the effect of suction in the chamber is also present within the hollow head, a hood disposed within the hollow head and opening to the interior of the receptacle, said hood having a small opening communicating the interior of the hood with the interior of the hollow head, and means to close the hood including a

5 felt wall through the interstices of which the powdered material is drawn from the receptacle.

14. A device for providing controlled injection of dry powdered material into a chamber subjected to suction, comprising a receptacle to hold a supply of the dry powdered material, a hollow head closing the receptacle, means to communicate the interior of the hollow head with the chamber, whereby the effect of suction in the chamber is also present within the hollow head, a metal wall having a part clamped between the receptacle and the hollow head and having a small opening therein, a chamber with which the interior of the hollow head is communicated through said opening, said chamber having a felt wall through the interstices of which powdered material passes from the receptacle into the chamber and then through the opening into the hollow head.

20 25. 15. A device of the character described, comprising, a receptacle for powdered material, a detachable hollow head closing the receptacle, said hollow head having an outlet through which material may be drawn by suction, a flanged hood disposed between the head and the receptacle, said flanged hood having an opening to communicate its interior with the hollow head, means to close the open end of the hood including a tubular felt member through the interstices of which dry powdered material passes from the receptacle 30 into the hood for passage through the opening therein into the head, and common means to maintain the tubular felt member assembled with the hood and to adjust the state of compression of said felt member.

35 40. 16. A device of the character described comprising, a receptacle for dry powdered material, a hollow head detachably secured to the open end of the receptacle to close the same, a flanged hood having its flange clamped between the hollow head and the receptacle and having a small opening to communicate the interior of the hollow head with the interior of the hood, a stud carried by the head and extending through the hood, a tubular felt member encircling the stud and engaging the hood to form a continuation of the chamber afforded thereby, and means carried by the stud to compress the felt member and cooperate therewith to completely close the chamber formed by the felt member and the 50 hood whereby the only passage from the receptacle into said chamber and consequently the interior of the hood is through the interstices of the felt member.

45 55. 17. A device of the character described, comprising a receptacle for powdered material, a hollow cap closing the receptacle and affording an outlet for the material from the receptacle, and a barrier carried by the cap to separate the receptacle from the interior of the cap, said barrier including a wall of fibrous material through the interstices of which the powdered material passes from the receptacle into the cap interior.

60 65. 18. A device to afford controlled injection of dry powdered material into a chamber subjected to suction, comprising, a receptacle for the material, a hollow head closing the receptacle and communicating with said chamber, a barrier to separate the receptacle from the hollow head including a wall of fibrous material through the 70 interstices of which the material is drawn by suction, and an adjustable air bleed leading to the interior of the hollow head to control the effect of suction on the material through the interstices of the fibrous barrier.

19. A device to afford controlled injection of dry powdered material into a chamber subjected to suction, comprising a receptacle for the material, a hollow head closing the receptacle and communicating with said chamber, a barrier to separate the receptacle from the hollow head including a wall of fibrous material through the

interstices of which the material is drawn by suction, and controlled air bleeds leading to the hollow head and to the receptacle to adjust the effect of suction within the hollow head and the receptacle, and thereby regulate the flow of material through the interstices of the fibrous wall. 5

CARL R. ROLEN.
